(57) **CLAIM**

I claim the ornamental design for a coffee grinder, as shown and described.

DESCRIPTION

The file of this patent contains at least one drawing/photograph executed in color. Copies of this patent with color drawings will be provided by the office upon request and payment of necessary fee.

FIG. 1 is a rear, bottom right side perspective view of a coffee grinder, showing my new design without a logo;
FIG. 2 is a right side elevational view thereof;
FIG. 3 is a left side elevational view thereof;
FIG. 4 is a front elevational view thereof;
FIG. 5 is a top plan view thereof; and
FIG. 6 is a bottom plan view thereof.

FIG. 7 is a rear, bottom right side perspective view of a coffee grinder, showing a second embodiment of my new design with a logo;

FIG. 8 is a front elevational view of FIG. 7;
FIG. 9 is a right side elevational view of FIG. 7;
FIG. 10 is a left side elevational view of FIG. 7;
FIG. 11 is a top, right side perspective view of FIG. 7;
FIG. 12 is a top plan view of FIG. 7; and,
FIG. 13 is a bottom plan view of FIG. 7.

The “COMANDANTE” logo and word depicted in FIGS. 7-13 and the design mark depicted in FIGS. 7 and 13 forming part of the claimed design are registered trademarks owned by Bernd Braune, the Applicant for the claimed design.

The dashed boundary lines in FIG. 5 show unclaimed boundaries between claimed and unclaimed subject matter.
